PRODUCTION OF ORGANIC COMPOUNDS
FROM METHANE SULFONIC ACID

Aristid V. Grosse, Haverford, and John C. Snyder,
Darlington, Pa., assignors to Houdry Process
Corporation, Wilmington, Del., a corporation
of Delaware

No Drawing. Application March 26, 1947,
Serial No. 737,408

10 Claims. (Cl. 260—456)

1

This invention relates to processes for the decomposition of methane sulfonic acid and to the products formed thereby. This application is a continuation-in-part of our co-pending application, Serial No. 673,628, filed May 31, 1946, now Patent No. 2,492,983, issued on January 3, 1950.

In our pending application we have disclosed that by subjecting methane sulfonic acid to elevated temperatures, such as temperatures in the range of 225° to 500° C., the methane sulfonic acid is decomposed and sulfur dioxide and methanol, in free or combined form, are among the products of decomposition. The present invention is based on the discovery that the decomposition or pyrolysis of methane sulfonic acid can be accelerated by carrying out the reaction in the presence of a methane sulfonate of a metal below (and not including) magnesium in the electromotive series of metals (as set forth at the bottom of page 1074 of the sixth edition of Lange's "Handbook of Chemistry," Handbook Publishers, Inc., Sandusky, Ohio, 1946). Such metals have moderate to weak base forming properties and are exemplified by beryllium, aluminum, silver, thorium, mercury, the rare earths, bismuth, lead, iron, and the like. Moreover, we have found that methane sulfonic acid can be decomposed so that one or more derivatives of methanol, such as methyl methane sulfonate and dimethyl ether, are among the products of the overall reaction, and that good yields of such compounds can be obtained by the processes herein described.

The decomposition of methane sulfonic acid to form methyl methane sulfonate affords a simple method for obtaining a compound which has previously been difficult to prepare. Attempts to prepare this compound by the usual methods of ester synthesis, such as the esterification of the alcohol or an alcoholate with the acid, acid halide or acid anhydride, have not been successful under conditions which generally produce good yields of esters. Other methods, such as the isomerization of dimethyl sulfite, produce undesirably low yields of the ester.

The methane sulfonic acid to be employed in the processes herein set forth can be obtained by methods known to the art, such as by hydrolysis of methyl sulfonyl halides, by oxidation of methyl thiocyanate, methyl sulfonic acid or methyl mercaptan and the like, but we prefer to obtain it by direct sulfonation of methane as disclosed and claimed in our co-pending application, Serial No. 673,627, filed May 31, 1946, now Patent No. 2,493,038, issued January 3, 1950. We

prefer to use the methane sulfonic acid in the free state except insofar as it may react with compounds of metals added to accelerate the decomposition as described herein; and in any event, the acid should not be in the form of an alkali metal salt since the controlled decomposition of the alkali metal salt to form methanol and derivatives of methanol is difficult if not impossible.

- 10 As disclosed in our prior application, the thermal decomposition may be effected at preferred temperatures in the range mentioned above, an especially suitable temperature being about 325° C., as by refluxing the free methane sulfonic acid
15 at atmospheric pressures. In performing the refluxing operation, an inert gas such as nitrogen, hydrogen, carbon dioxide or the like may be used to sweep out the methanol and sulfur dioxide or other reaction products, or the temperature of
20 the condenser or dephlegmator may be adjusted to allow these products to pass overhead. When a portion of the methanol produced reacts with the undecomposed methane sulfonic acid to form an ester, a fraction composed principally
25 of the ester may be obtained by carrying the decomposition reaction substantially to completion or by separating the ester and the free methane sulfonic acid, as by distillation. If methanol is desired as the final product, the ester can then be easily hydrolyzed to obtain
30 methanol and the free acid, which may then be subjected to decomposition to produce additional methanol or the ester may be both hydrolyzed and the free acid decomposed in the same operation as described below. The process may also
35 be carried out by passing the methane sulfonic acid through a decomposition zone, such as a tube either empty or filled with an inert material for heat capacity. This zone is held at a suitable temperature within a preferred range of
40 300° to 400° C. The methane sulfonic acid may be injected into the reaction zone as a liquid or may enter the reaction zone as a vapor, either alone or in conjunction with an inert gas. In
45 the thermal decomposition process of our pending application, dimethyl ether may be among the reaction products.

In accordance with the present invention, we accelerate the formation of methanol and/or derivatives of methanol, such as dimethyl ether and methyl methane sulfonate, from methane sulfonic acid by subjecting methane sulfonic acid to pyrolysis at elevated temperatures selected to promote the removal of sulfur dioxide from methane sulfonic acid, such as temperatures

within the range of 225° to 500° C., a particularly effective range being 280° to 400° C., in the presence of a compound of a metal referred to above. Compounds of metals which have been found to be particularly effective in accelerating such processes are referred to herein as catalysts.

The compounds of the metals used to accelerate the decomposition of the methane sulfonic acid and the formation of secondary reaction products such as methyl methane sulfonate and dimethyl ether may be added to the methane sulfonic acid as a compound or salt which thereafter reacts with the methane sulfonic acid and thereby forms a metallic methane sulfonate or the compound of the metal may be supported on or associated with an inert, preferably porous, carrier, such as silica gel, pumice, or kieselguhr, and thereafter contacted with the methane sulfonic acid in the vapor state. Thus, for example, the compound of the metal may be an oxide, hydroxide, or hydrous oxide or a salt having an anion, such as a carbonate or a sulfide, which produces a gas when the salt reacts with the free methane sulfonic acid. Alternatively, the compound of the metal may be a salt having an anion which is substantially unreactive when dissolved or suspended in the methane sulfonic acid, such as sulfate, phosphate, or borate. The compound of the metal may have an anion which forms, by interaction with the methane sulfonic acid, a distillable liquid, such as acetate or similar organic anions. Any of the above compounds may be used to impregnate an inert carrier, preferably porous, and the impregnated carrier thereafter contacted with methane sulfonic acid, preferably in the vapor phase. Alternatively, the compound of the metal may be a colloidal gel, such as alumina gel, associated with another colloidal gel in a contact mass such as a silica-alumina gel. In general, the amount of the compound of the metal employed is less than that equivalent to one mole of the metallic element to six moles of methane sulfonic acid, while amounts as low as those equivalent to one mole of the metallic element to 500 moles of methane sulfonic acid have been found effective.

Water, preferably in the form of steam, may be used with the methane sulfonic acid to aid the decomposition or pyrolysis process, particularly when methanol is the desired product. When water is present during the pyrolysis, the methane sulfonic acid can conveniently contain the methyl ester thereof ($\text{CH}_3\text{SO}_3\text{CH}_3$), particularly when the methane sulfonic acid is, at least in part, derived from the sulfonation of methane. In a continuous process such as described above, the methyl ester may be added separately to the reaction zone, in which event, water or steam may be added to the methyl ester before it enters the zone. Such mixtures of methyl methane sulfonate and water may be preheated to aid the hydrolysis of the ester. The methyl methane sulfonate is easily hydrolyzed and thus it furnishes additional quantities of methanol and methane sulfonic acid when added to a reaction zone in which methane sulfonic acid is being thermally decomposed to methanol in the presence of steam. When mono-sulfonated derivatives of methane, such as either methane sulfonic acid or its methyl ester or both, are charged to the thermal decomposition zone, the effluent mixture therefrom may be cooled to a temperature somewhat above the boiling point of methanol, such as about 100° C., in order to condense any unconverted methane sulfonic acid or any high

boiling material present or formed in the process, the cooled vapors separated and the methanol, lower boiling organic products, and sulfur dioxide recovered.

We obtain derivatives of methanol, such as methyl methane sulfonate or dimethyl ether or both, by subjecting methane sulfonic acid to pyrolysis conditions in the presence of a catalyst as herein described and thereafter separating at least one of such derivatives from the resultant products. The yield of such derivatives of methanol may be increased by increasing the time of contact of the methane sulfonic acid and the methanol liberated in the decomposition. Thus we may reflux methane sulfonic acid, at atmospheric pressure, to which acid a compound of a metal may be added to accelerate the decomposition as described above, under dephlegmating conditions such that any methyl methane sulfonate formed distills over and thereafter separate the distillate into fractions by further distillation, extraction or other methods known to the art and thus obtain fractions consisting of methanol or one of its derivatives, methyl methane sulfonate or dimethyl ether. Alternatively, we may employ a distillation column from which methyl methane sulfonate is taken off as a side stream and any methanol formed is totally refluxed. When it is desired to increase the yield of dimethyl ether, dephlegmating conditions may be maintained so as to retain as much as possible of the methyl methane sulfonate in the decomposition zone. Alternatively, any methyl methane sulfonate in the distillate may be recycled to the decomposition zone.

In order to illustrate the present invention but not to be construed as a limitation thereof, the following examples are given:

Example I

(A) Methane sulfonic acid was refluxed for four hours at about 310° C. under heating and dephlegmating conditions such that the vapors which distilled over were at a temperature slightly below 250° C. The distilled vapors were passed first through an ice cooled trap and then through a trap cooled with solid carbon dioxide from which sulfur dioxide was recovered.

The material collected in the ice cooled trap was liquid and formed two layers. This material, on distillation and drying, yielded some undecomposed methane sulfonic acid (estimated to be about 12% of the original acid) and an amount of methyl methane sulfonate equivalent to about 31% of the original acid (based on conversion of two moles of the acid to one mole of ester).

Distillation of the residue of the refluxing operation yielded pure methane sulfonic acid (about 56% of the original acid) and a carbon residue equivalent to less than 1% of the original acid.

(B) Methane sulfonic acid was heated with silver carbonate (0.045 mole of Ag_2CO_3 per mole of acid) until the latter dissolved and evolution of carbon dioxide ceased. The resultant solution which was clear, was refluxed for 1.25 hours under conditions similar to those described under (A).

Examination of the residue and products indicated that the reaction products consisted predominately, if not completely, of methyl methane sulfonate. This ester saponified readily with sodium hydroxide to yield methanol. The amount of the methyl methane sulfonate recovered was equivalent to about 49% of the original acid.

Comparison of the above results with those set

forth under (A) shows that the metal compound present accelerated the reaction, giving a higher yield in a shorter time.

Example II

Methane sulfonic acid and finely ground aluminum oxide (0.013 mole of Al_2O_3 per mole of acid) were subjected to refluxing for 0.5 hour under the same conditions as in Example I (B), during which time about half of the aluminum oxide dissolved. About 16% of the acid was converted to ester.

Example III

Methane sulfonic acid and bismuth subcarbonate (0.0023 mole of $Bi_2O_3 \cdot CO_2 \cdot H_2O$ per mole of acid) were initially heated until a clear solution resulted and the evolution of carbon dioxide ceased. The clear solution was subjected to refluxing under the same conditions as in Example I (B) for 1.33 hours during which time methyl methane sulfonate was formed in an amount equivalent to about 45% of the original acid with the simultaneous evolution of sulfur dioxide in an amount equivalent to a little over 50% decomposition.

Example IV

Methane sulfonic acid was refluxed for four hours at about 300° to 310° C. in equipment which provided fractionation of the evolved vapors, by placing a column 75 mm. high filled with $\frac{1}{8}$ " glass helices above the vessel in which the acid was heated. The temperature of the distillate removed from the top of the fractionating column was maintained at about 100° C. The distillate was collected as in Example I. About 43% of the acid decomposed under these conditions. Separation and analysis of the various fractions and the residue showed that, based on 100% decomposition of the acid, the following products are formed:

	Percent
Methyl methane sulfonate	43
Dimethyl ether	35
Methanol	15
Carbonaceous material	2.2

Additional runs using similar conditions to those given above, demonstrated that either mercuric oxide or thorium dioxide accelerated the decomposition.

Obviously many modifications and variations of the invention as hereinbefore set forth may be made without departing from the spirit and scope thereof and therefore only such limitations should be imposed as are indicated in the appended claims.

We claim as our invention:

1. The process which comprises thermally decomposing methane sulfonic acid in the free state and in the presence of a small quantity, sufficient to catalyze the decomposition, of a methane sulfonate of a metal below magnesium in the electro-motive series of metals at a temperature of at least 225° C. and below 500° C. in a decomposition zone to form decomposition products comprising at least one compound selected from the group consisting of methanol, dimethyl ether and methyl methane sulfonate and removing said decomposition products from the decomposition zone.

2. The process which comprises thermally decomposing methane sulfonic acid in the free state and in the presence of a small quantity, sufficient to catalyze the decomposition, of a methane sul-

fonate of a metal below magnesium in the electro-motive series of metals at a temperature of at least 300° C. and below 400° C. in a decomposition zone to form decomposition products comprising at least one compound selected from the group consisting of methanol, dimethyl ether and methyl methane sulfonate and removing said decomposition products from the decomposition zone.

3. The process which comprises thermally decomposing methane sulfonic acid in the free state and in the presence of a small quantity, sufficient to catalyze the decomposition, of a methane sulfonate of a metal below magnesium in the decomposition zone to form decomposition products comprising at least one compound selected from the group consisting of methanol, dimethyl ether and methyl methane sulfonate, removing said decomposition products from the decomposition zone and separating at least one compound selected from the group consisting of methanol, dimethyl ether and methyl methane sulfonate from said decomposition products.

4. The process of claim 3 wherein the metal is aluminum.

5. The process of claim 3 wherein the metal is bismuth.

6. The process of claim 3 wherein the metal is mercury.

7. The process which comprises thermally decomposing methane sulfonic acid in the free state and in the presence of a small quantity, sufficient to catalyze the decomposition, of a methane sulfonate of a metal below magnesium in the electro-motive series of metals in a decomposition zone to form decomposition products comprising dimethyl ether, removing said decomposition products from the decomposition zone and separating dimethyl ether from said decomposition products.

8. The process of claim 7 wherein the metal is mercury.

9. The process which comprises thermally decomposing methane sulfonic acid in the free state and in the presence of a small quantity, sufficient to catalyze the decomposition, of a methane sulfonate of a metal below magnesium in the electro-motive series of metals in a decomposition zone to form decomposition products comprising methyl methane sulfonate, removing said decomposition products from the decomposition zone and separating methyl methane sulfonate from said decomposition products.

10. The process of claim 9 wherein the metal is mercury.
